UNITED STATES PATENT OFFICE.

EMILY ELLISON, OF IRLAMS-O'-TH'-HEIGHT, NEAR MANCHESTER, ENGLAND,
ASSIGNOR OF ONE-HALF TO W. T. ELLISON & COMPANY, LIMITED, OF
IRLAMS-O'-TH'-HEIGHT, NEAR MANCHESTER, ENGLAND.

DRAWING-BOARD AND T-SQUARE.

SPECIFICATION forming part of Letters Patent No. 723,518, dated March 24, 1903.

Application filed October 4, 1902. Serial No. 125,906. (No model.)

To all whom it may concern:

Be it known that I, EMILY ELLISON, a subject of the King of Great Britain and Ireland, residing at 53 Bolton road, Irlams-o'-th'-Height, near Manchester, in the county of Lancaster, England, have invented new and useful Improvements Applicable to Drawing Boards and T-Squares to be Used Therewith, of which the following is a specification.

10 This invention relates to improvements upon that type of drawing-boards and T-squares used by engineers, architects, surveyors, and other draftsmen and lecturers wherein magnetic appliances are employed 15 for keeping the head of the T-square always in close contact with the working edge of the drawing-board.

According to my invention I propose to plane or otherwise form a groove—say about 20 half inch or more and about three-sixteenths of an inch wide (either more or less to suit my purpose)—in the left-hand and lower edges of the drawing-board and to insert therein and secure by means of pins or otherwise a 25 strip of soft iron of such a width that its outer edge may project slightly beyond the edge of the board. This method of fixing the soft-iron strip will not only prevent any liability of its becoming loose, but as it is in its 30 strongest possible form will not be liable to get out of true, even if the board warps, and will also render it more durable. Also hitherto in applying a magnet to the head of the T-square to cause its adhesion to the edge 35 of the board it has been the practice to use a straight or curved magnet which has its poles a considerable distance apart. Thus its range of working is very limited if, say, you are working at the top or bottom of your 40 board the current is broken, owing to one of its poles being off the strip, therefore rendering the magnet ineffective. To remedy these defects, I propose according to my invention in the first place to use a number of small 45 horseshoe or U magnets permanent or electric—say two or more to suit my purpose—which I entirely embed or inclose in the head of the T-square, with the exception of their poles, which may either be flush or project 50 slightly beyond the surface of the wood on

the inner or working side of the head, and to so arrange these magnets above and below the center of the blade, that however near the latter may be moved to the top or bottom of the board, there will always be one or 55 more magnet or magnets in effective action, and therefore the T-square will not be liable to become loose accidentally and fall from its position on the board.

On the accompanying drawings, which form 60 part of this specification, Figure 1 is a face view, Fig. 2 an edge view, and Fig. 3 a section, of the edge of the drawing-board with a soft-iron strip shown as applied thereto. Fig. 4 is a face view, Fig. 5 an edge view, and 65 Fig. 6 a sectional view, of the head of the T-square made according to my invention. Fig. 7 is a view, on a reduced scale, showing the improved drawing-board and T-square together as they appear when in use. 70

The head of the T-square for use with this drawing-board (see Figs. 4, 5, and 6) I prefer to make of two thicknesses of wood f g, glued or cemented together and fastened with screws h. (See Figs. 4, 5, and 6.) In one of these pieces of wood I embed a series of magnets—say, for example, five—of a horseshoe or U form, so as to be flush with the surface, and then I apply the other piece and fix it firmly thereon, as described, so that the magnets are entirely inclosed in the wood with the exception of their poles, which are flush with the outside of the wood or project only very slightly therefrom on the working edge of the head. According to Fig. 6 I prefer to 85 make the magnets laminated by two, three, or more layers of steel U-shaped plates, (according to the weight or size of the T-square,) as they are stronger in their action, but they may also be of a solid bar bent to the U shape. 90

It will be evident that when the head of the T-square is made according to my invention and provided with a series of magnets, as described, when used in connection with a drawing-board or lecture-board, (see Fig. 7,) the 95 blade may be raised to the upper edge of the paper, so that a considerable portion of the head projects above the top of the board and that those magnets which are below the edge of the board will have their circuits unbroken 100

and will retain the square in position even if the board should be placed in almost a vertical position or the most acute angle.

I claim as my invention—

- 5 1. A T-square having a number of horseshoe-magnets embedded in the head, side by side longitudinally thereof, the poles of all of which extend to and are exposed at the surface of the inner edge and are adapted to be
- 10 rested against the edge of the drawing-board, in combination with a drawing-board having an iron strip at its edge, substantially as described.
- 15 2. A T-square, having a number of laminated horseshoe-magnets embedded side by

side longitudinally in the head, the poles of all of which extend to and are exposed at the surface of the inner edge, in combination with a drawing-board having a bar of soft iron set into its edge and pins passing through the board and iron to hold it in place, substantially as described. 20

In testimony whereof I have signed my name to this specification in the presence of two subscribing witnesses.

EMILY ELLISON.
